United States Patent Office

Des. 198,323
Patented June 2, 1964

198,323

BUFFET

Melbourne F. Smith, Jr., 101 Maehill Drive, Lenoir, N.C.

Filed Jan. 15, 1964, Ser. No. 78,214

Term of patent 14 years

(Cl. D33—13)

FIG-2

The back of the buffet is substantially plain and unornamented.

I claim:

The ornamental design for a buffet, substantially as shown and described.
